UNITED STATES PATENT OFFICE.

HECTOR LEIGHTON DAVIES, OF GOWERTON, NEAR SWANSEA, AND SAMUEL REES COUND, OF ABERAVON, WALES.

ROLLING MILL FOR THE PRODUCTION OF METAL SHEETS OR PLATES.

Application filed January 9, 1926, Serial No. 80,259, and in Great Britain February 2, 1925.

This invention relates to processes and apparatus for the production of metal sheets or plates, according to which the material is subjected to repeated sequences of operations comprising in each sequence the steps of heating, rolling, doubling and trimming.

In the practice at present most generally in use, these successive sequences of operations are performed in a single set of apparatus comprising a furnace, two rolling mills and a doubler and trimmer, each of these subsidiary machine elements being attended to by one or more operators.

In such an arrangement, a workpiece has to be operated upon repeatedly by each of the individual machine elements of the apparatus so that necessarily the whole range of operations has to be completed thereon before a second workpiece can be taken in hand. Evidently therefore, only one of the subsidiary machine elements of the apparatus being in operation at a given moment, the other subsidiary machine elements of the set, together with their respective operators, remain idle for the greater part (roughly three fourths) of the time. This method of working does not make full use of the capabilities of the apparatus and operators, and is consequently wasteful in time and wages, so that it results in an unnecessarily high cost of production.

An additional source of delay and consequent uneconomical working is to be found in the arrangement of apparatus at present commonly in use, in which the rolling mills, comprising a roughing mill and a finishing mill for each set of apparatus, are arranged in a plurality of sets—alternately a roughing and a finishing mill—upon one common continuous shaft. It has also been proposed to put a roughing mill on such shaft beside or between two finishing mills provided with their appropriate accompanying doublers, trimmers etc., but as each of these rolling mills is attended to by two operators, a "roller man" who attends to the feeding of the material and a "behinder" who attends at the rear side of the mill to return the material back to the "roller man" after each "pass" through the rollers, and inasmuch as the continuous shaft of the rolling mills constitutes a barrier between the "behinder" and the "doubler" (viz, the operator attending the doubling and trimming apparatus), the "behinder", after the work-

piece has been subjected to the last pass through the mill, cannot pass it on directly to the "doubler", but returns it to the "roller man", who will then hand it on to the "doubler". The "roller man" is thus taken from his proper work and the feeding of fresh material interrupted while he is so occupied and while the "behinder" stands idle for a corresponding period of time. In the finishing operations (rolling "fours and eights") the workpiece is subjected to two passes through the mill so that the waste of time from this cause alone amounts to about 20 to 25%; while for roughing, which requires six passes and for rolling "doubles" which may require three passes, the loss of time will be proportionately less.

With a view to obviate the objections referred to, which are inimical to economical production of metal sheets and plates, we have in our prior application, No. 746,110, filed October 27, 1924, disclosed a method and arrangement of apparatus for the performance of the usual four sequences of operations, whereby "boxes" or "packs" of eight sheets are produced, which enables not only all the machine elements of the apparatus to be concurrently employed in the performance of their tasks upon a plurality of workpieces, fed in quick succession from apparatus to apparatus, but which also enables the workpieces to be fed uninterruptedly forward from operator to operator, so that back-handling of the workpiece and consequent delay and waste of time are entirely avoided.

Having regard to the fact that each rolling operation consists in a number of passes of the workpiece through the mill and that this number varies with the successive stages, as for instance, six passes for roughing, three passes for "doubles" and two passes for "fours" or "eights", it is evident that the time periods occupied by the several rolling operations of the sequence vary correspondingly.

It follows that in the arrangement proposed in our prior application hereinbefore referred to, in which a separate rolling mill is provided for each stage, the roughing mill will not be able to keep pace with the work performed by the mills of the succeeding stages or in other words the three finishing mills and their operators will not be occupied to the full of their capacities.

The finishing mills might therefore be given additional work to perform to occupy them for a period equal to the period occupied by the roughing mill for its appointed task.

Based on this consideration, it is the object of the present invention to so arrange the several elements of the apparatus and to so apportion the work to be performed by each of the said elements that thereby more favorable and more economical working conditions are established.

According to the present invention there are provided for the performance of a complete sequence of operations, four furnaces, three rolling mills having separate individual driving shafts and two doublers and so arranged and operated that each of the rolling mills, doublers and trimmers per 10 forms the respective operations of two successive stages to occupy the said elements substantially in synchronism, while the work in consequence of the arrangement of the rolling mills one behind the other passes 15 through and between the different elements of the apparatus and from operator to operator so as to involve the minimum of handling.

In order to attain said synchronism the work to be performed in some of the operations is divided between two of the machine elements.

Thus, for example, an apparatus for producing metal sheets or plates in boxes of 20 eight, will comprise the combination of four heating furnaces with three rolling mills and two doublers and trimmers; and the work will be distributed in such a manner that, while the heating of the metal is performed at each stage of the process in a separate furnace, each of the rolling mills and each of the doublers and trimmers performs the work of the respective operations of two succeeding stages. In such arrangement the first rolling mill will perform the rolling of the bars and of the singles, the second the rolling of the doubles or pairs and part of the four fold sheets, and the third the rolling of the remaining four folds and the eight fold sheets, while the first doubler will double the singles into doubles and part of the two fold sheets into four folds, and the second doubler will double the other part of the two folds into four folds and all the four folds into eight fold sheets. The rolling of any individual piece of work at each stage is, however, completed by one rolling mill.

Preferably the rolling mills are arranged on different shafts placed one behind the other, each being independently driven in the manner described in our aforesaid prior application. This arrangement offers the great advantage that the "behinder" can pass the workpiece directly on to the

"doubler", thereby avoiding the waste of time, which, as has hereinbefore been fully explained, is unavoidable with the arrangements at present in use.

The rolling mills may, however, be arranged as hitherto, in alignment on a common shaft, if it should be desired to adapt existing plants for the performance of the present invention. Obviously the advantage mentioned hereinbefore to be gained from the method of arranging the rolling mills on parallel shafts, would be lost in this alternative arrangement.

The accompanying drawings illustrative diagrammatically two forms of arrangement of the apparatus embodying the invention.

Fig. 1 shows the arrangement of two complete sets of apparatus, each comprising the required number of furnaces, rolling mills and doublers and trimmers, symmetrically arranged in relation to the driving means, and having the rolling mills of the two sets which perform the same stages in the sequence of operations coupled in pairs upon parallel shafts.

Fig. 2 shows the arrangement of a single set of apparatus in which the three rolling mills of the set are mounted on a single common shaft.

Either of the two figures illustrates the approximate relative positions of the four furnaces, A, A¹, A², A³, the three rolling mills B, B¹, B², and the doublers and trimmers C, C¹, as well as in one of the sets the paths followed by the workpieces in the course of their progress through the apparatus. The letters and numerals (R), (1) (2), (4), (8), and (F) marked on the path lines are indicative of the respective stage to which the work has progressed; (R) designating raw material (bar); (1), (2), (4), (8) representing the workpiece in single, double, four fold or eight fold sheets respectively, and (F) the metal in its final stage of "boxes" or "packs" of eight sheets.

As will be seen in Fig. 1, the three shafts D, D¹, D², of the three pairs of rolling mills B, B¹, B², are each independently driven by means of belts or ropes H, H¹, H² respectively from the pulley G mounted on the shaft of an electric motor E.

In Fig. 2 the rolling mills B, B¹, B², are mounted on the common shaft D³, which is driven by means of the belt or rope drive H³, from the source of power which in this case is assumed to be the steam engine E¹.

It will be noticed in following the path (R) from the furnace A, to rolling mill B, that the workpiece on having attained a predetermined length issues therefrom in single sheets (1), is brought to furnace A¹ for reheating and again passed through the rolling mill B until rolled to the desired length. It is then sent on to doubler C,

folded in two and forwarded along path (2) to rolling mill B¹ after having been reheated in furnace A². As will be seen the double sheets rolled to required length in mill B¹ are 5 now directed in equal numbers to the doubler C by path (2) and to the doubler C¹ by path (2¹) where they are folded into fours and brought for reheating along paths (4) and (4¹) to the furnaces A² and A³ respectively. 10 The four fold sheets from furnace A² are brought to rolling mill B¹ and from furnace A³ to the rolling mill B², from both of which mills they are brought to the doubler C¹ to be folded into eight, and finally reheated in 15 furnace A³, rolled at B² and delivered at (F) in the form of "boxes" of eight sheets; there is of course no doubling or trimming in this last stage.

The workpieces are obviously brought by 20 the shortest paths from one subsidiary machine element to another and the paths shown in the drawing are merely lines to indicate the start and finish of each travel, as well as the direction of feed and delivery in 25 each of the machine elements.

We claim:—

1. A rolling mill installation for producing eight-fold sheets and plates from metal bars, comprising a mill for rolling the raw 20 bars into singles and for subsequently rolling the singles; a doubler for folding the

singles into doubles and for subsequently folding part of the doubles into "fours"; a second mill for rolling the doubles and for subsequently rolling part of the "fours"; a 35 second doubler for folding the remainder of the doubles into "fours" and for subsequently folding all the "fours" into "eights"; a third mill for rolling the remainder of the "fours" and for subsequently rolling all 40 the "eights"; and furnaces for heating the work between the rolling and folding operations.

2. A method of producing multifold metal sheets and bars, comprising the steps 45 of rolling raw metal bars in a mill while hot into singles and subsequently rolling the singles in the same mill; folding the singles into doubles in a doubler and subsequently folding part of the doubles in the same 50 doubler into "fours"; rolling the doubles in a second mill and subsequently rolling part of the "fours" in said second mill; folding the remainder of the doubles into "fours" in a second doubler and subsequently folding all 55 the "fours" into "eights" in said second doubler, rolling all the "eights" in a third mill; and heating the work between the rolling and folding operations.
